(57) **CLAIM**

The ornamental design for a webcam, as shown and described.

DESCRIPTION

FIG. 1 is a front perspective view of a webcam showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view thereof, shown in an alternate first configuration;

FIG. 10 is a front perspective view thereof, shown in an alternate second configuration; and,

FIG. 11 is a front perspective view thereof, shown in an alternate third configuration.

The broken lines depict portions of the webcam in which the design is embodied that form no part of the claimed design.
